UNITED STATES PATENT OFFICE.

SAMUEL M. ALK, OF BROOKLYN, NEW YORK.

ROLLING TOY.

Application filed October 25, 1921. Serial No. 510,307.

To all whom it may concern:

Be it known that SAMUEL M. ALK, citizen of the United States, residing at Brooklyn, New York, has invented a new and useful

5 Improvement in Rolling Toys, of which the following is a specification.

My invention relates to children's toys and has particular reference to a ball or other rolling toy which when rolled upon 10 any convenient surface will accumulate sufficient power when its impetus has been expended to reverse its direction of travel and return automatically to approximately the starting point, and which is inexpensive to 15 manufacture and simple in operation.

The object of this invention is to provide such a toy wherein relatively operating springs are so mounted with respect to the axis of a casing that movement of the latter 20 in one direction will tend to wind up but one of said springs, the other remaining inoperative until the first named spring has spent its accumulated energy.

A further object of the invention is to so 25 construct and arrange the operating mechanism that it may be entirely contained within a casing, thereby tending to produce a more or less mystifying phenomenon as the sphere seemingly unaided reverses its 30 direction of travel and returns to the starting point.

Other objects will appear throughout the 35 following specification and be pointed out in the appended claims, reference being had to the accompanying drawing, wherein—

Fig. 1, is an elevational view of a ball with a portion of its casing broken away to show the operating mechanism.

Fig. 2, is a substantially vertical sectional 40 view taken on the lines 2—2 of Figure 1.

Fig. 3, is a perspective view of the means used to wind each spring separately depending upon the rotation of the casing.

Referring to the drawing, 10 denotes a 45 hollow spherical casing within which is secured an annular ring 11 having diametrically disposed bearing collars 12 projecting inwardly toward each other. These 50 bearings are axially aligned with each other and loosely support the opposite ends of an axial-rod 13 which carries midway of its length and at right angles thereto a depending weight supporting rod 14 and which is provided with a pair of slots 15 extending 55 from points closely adjacent each side of the rod 14, and on a plane diametrically op-

posite to the rod 14, to points closely adjacent the inner faces of the collars 12. The lower end of the rod 14 carries the central portion of a crescent shaped weight 16 the 60 outer surface of which is concentric with the inner periphery of the ring 11 and which extends upwardly at each end thereof a sufficient distance to loosely bear about the bearing collars 12. Slidably mounted in 65 each of the slotted openings 15 of the axial-rod 13 are flat spring actuating members 17 having slotted openings 17^a adjacent their opposite ends, the axes of which are substantially parallel with the axis of the rod 70 14, and which loosely surround the inner end strands of the last coils of a pair of helical springs 18 and 19, the opposite ends of the springs being anchored permanently to the bearing collars 12 by means of staples 75 20. It will be noted that these springs 18 and 19 are loosely supported axially about the oppositely extending portions of the axial-rod 13 i. e., at each side of the rod 14, and that the strand of the last coil is 80 threaded through one of the slots 17^a, then through the other slot 17^a at the opposite end of the member 17, and thereafter bent back upon itself to form a pivot 21. Furthermore, with particular reference to Figure 3, it will be noted that the coils of the springs 18 and 19 are oppositely disposed, i. e., the knot 21 of one coil is above the end 85 of one slide member 17 at one side of the axial-rod 13, while the other knot of the 90 other coil is above the end of the other slide member at the opposite side of the axial-rod 13.

The operation of the device is as follows:—Assuming the ball 10, shown in Figure 1, is to be rolled forward towards the observer, the weighted axial-rod 13 will remain stationary with respect to the revolving casing 10 and the staple 20 of spring 19 will rotate with the bearing collar 12 and 100 tend to wind up the spring itself closely about the portion of the axial-rod 13 to the left of the weight rod 14. The slide member 17 may or may not move axially of the slot 15 while the spring 19 is winding, but the 105 slide member 17 in the opposite slot 15 will ride outwardly away from the rod 14 and axially of the slot 15. This operation is caused by the rotation of the spring 18 about the axial-rod 13 in the same direction 110 as that of the spring 19 an operation due to the end of the spring 18 being secured to the

collar 12 which is turning with the casing 10. What actually happens is, that the coils of the spring 18 act as threads, and in the direction in which they are turning merely travel through the slots 17^a and convey the slide member 17 axially of its slot 15 in the direction of the pitch of the coils. When the ball 10 has spent its momentum in this direction the spring 19 will have been completely wound, whereupon with the weight 16 still holding the axial-rod 13 stationary with respect to the casing, the torsion of the spring 19 will have accumulated sufficient propelling energy to begin to unwind from the collar end, an operation which will reverse the movement of the casing 10 about the axis of rotation of the latter. In doing this the ball will return to substantially the point from which it started and the reverse rotation of the spring 18 will have returned the slide member 17 to its initial position. It will be understood that upon rolling the ball in a direction which is reversed from that which has just been described the spring 19 will remain inoperative and the other spring 18 will be wound about the axial-rod 13 until its accumulated power will react to automatically return the ball to its starting point.

Having fully described and ascertained the nature and operation of my invention, what I claim and desire to secure by Letters Patent is:

I claim:

1. In a toy of the character described, the combination with a revolving casing having a loosely disposed axial rod, of oppositely actuated coiled springs carried by the rod, a weighted member connected to said rod and adjustable means mounted in longitudinally disposed slots in said rod and comprising slotted members loosely embracing the coils of the springs, the inner coils of the springs being provided with enlarged tips to prevent further relative movement of the members in one direction.

2. In a toy of the character described, the combination with a spherical casing of oppositely disposed springs fixed at one of their ends to said casing and having their

axis in line with the axis of rotation of said casing, a weighted member loosely supported in said casing and normally remaining stationary with respect to said rotating casing, and means movable axially of said weighted member and over the coils of said springs in one direction and engaged with the opposite ends of said springs in the opposite direction whereby rotation of said casing in opposite directions will tend to tension one or the other of said springs.

3. In a revolving toy of the character described, rotating annular ring, a weighted rod loosely mounted in line with the axis of rotation of said ring and adapted to remain stationary with respect to the latter and having oppositely extending slots disposed longitudinally of said rod, slideable members having slots in opposite ends thereof and mounted in said slots, and coiled springs fixed at one of their ends to said annular ring and at their opposite ends loosely embraced by the slots in said slide members, whereby rotary movement of said ring in one direction will tend to wind one or the other of said springs about said rod, the other of said springs being rotated with the ring and moving its slide axially of said slot.

4. The combination, with a rotating frame, of oppositely actuated coiled springs, in line with the axis of rotation of said frame and secured at one of their ends thereto, a loosely mounted slotted axial rod carried by said frame axially of said springs and having a depending weight adapted to hold the rod stationary with respect to said frame, and means movable relatively of said axial rod and over the coils of said springs and in opposite directions, whereby the opposite ends of one or the other of said springs may be held stationary with respect to the other ends depending upon the direction of rotation of said frame about its rotary axis.

In testimony whereof, SAMUEL M. ALK, has signed his name to this specification this 13th day of October 1921.

SAMUEL M. ALK.
